UNITED STATES PATENT OFFICE.

BELA KORMENDY, OF CLEVELAND, OHIO, ASSIGNOR TO THE THEODOR KUNDTZ COMPANY, OF CLEVELAND, OHIO, A CORPORATION OF OHIO.

COMBINED CHAIR AND TABLE-LEAF.

1,203,204.

Specification of Letters Patent. Patented Oct. 31, 1916.

Application filed August 2, 1915. Serial No. 43,251.

To all whom it may concern:

Be it known that I, BELA KORMENDY, a citizen of the United States of America, residing at Cleveland, in the county of Cuyahoga and State of Ohio, have invented certain new and useful Improvements in a Combined Chair and Table-Leaf; and I hereby declare the following to be a full, clear, and exact description of the invention, such as will enable others skilled in the art to which it pertains to make and use the same.

This invention relates to improvements in a combined chair and table-leaf for use in assembly-rooms, lunch rooms, etc., and more especially to a chair which not only has an arm arranged at the right-hand side and above the seat of the chair and extending forwardly beyond said seat but comprises a standard instrumental in supporting said arm and provided with a slideway which extends up and down the standard and is engaged by a slide to which is pivotally connected a table-leaf which is arranged substantially vertically in the lower position of the slide and in position to be swung over the forward portion of the chair-arm upon the actuation of the slide from its lower into its upper position.

One object of this invention is to render a piece of furniture of the character indicated simple and durable in construction and of great convenience in assembly-rooms and lunch-rooms.

Another object is to provide means whereby the table-leaf is maintained in position vertically in the lower position of the hereinbefore mentioned slide and is not liable to displacement in said position of the slide.

With these objects in view, and to the end of attaining any other advantage herein-after appearing, this invention consists in certain features of construction and combinations and arrangement of parts herein-after described, pointed out in the claims and illustrated in the accompanying drawings.

In said drawings, Figure 1 is a side view of an arm-chair provided with a table-leaf in accordance with my invention. Fig. 2 is a top plan relative to Fig. 1. Fig. 3 is a vertical section on line 3—3, Fig. 1, looking rearwardly. Fig. 4 is a horizontal section on line 4—4, Fig. 3, looking downwardly. Fig. 5 is a horizontal section on line 5—5, Fig. 3,

looking downwardly. Fig. 6 is a vertical section showing the table-leaf actuated into its upper position preparatory to swinging said leaf onto the arm of the chair. Fig. 7 is a vertical section corresponding with Fig. 6, except that in Fig. 7 the table-leaf is shown swung onto said arm.

Referring to Figs. 1 and 2 of said drawings, A indicates the seat of an arm-chair, and B the back of the chair. C represents the arm of the chair, which arm is arranged at the right-hand side and above the seat A and extends forwardly beyond said seat in a horizontal plane and has its forward portion wider than its rear portion and forming a horizontally arranged shelf 10 which rests on top of and is rigid with a vertically arranged wooden standard D formed in any approved manner. The standard D is instrumental therefore in supporting the forward portion 10 of the chair-arm. The standard D is preferably provided under said portion of the chair-arm with a bracket 11 on which said arm rests. The standard D is braced, as at 12, from and rigid with the body of the chair.

The forward portion 10 of the arm C (see Figs. 2, 3, 6 and 7) is provided at its outer longitudinal edge with a recess 13 which extends from top to bottom of said arm. The standard D is provided at its outer side with two parallel metal bars d which are arranged vertically and secured to the standard in any approved manner and spaced longitudinally of the forward portion 10 of the chair-arm C. The bars d are shown extending into the recess 13, and said bars preferably extend from the top of the chair-arm vertically downwardly into suitable proximity to the lower end of the standard D and are instrumental in forming a vertically arranged slideway which is arranged between and extends longitudinally of said bars, and said slideway is engaged by a metal slide E movable vertically along said slideway. The bars d are provided with flanges 14 which extend from end to end of said bars and overlap the outer side of the slide E and are long enough to prevent displacement of the slide laterally outwardly from the standard D in any position of the slide.

By the construction hereinbefore described it will be observed that the standard D is provided at its outer side with a slideway which extends vertically downwardly from

the outer longitudinal edge of the shelf-forming forward portion 10 of the chair-arm C and is engaged by a slide which in its lower position (see Figs. 1 and 3) rests 5 on seat-forming members 15 which are arranged at the outer side of the lower end-portion of said standard and removably secured to the standard by screws 16 shown in dotted lines Fig. 3. Each bar d is provided at its upper end with a lug 17 which is arranged next above the path of the slide E and forms a stop arranged to limit upward movement of the slide and prevents movement of the slide out of engagement 10 with the engaging slideway formed by and between the bars d as hereinbefore indicated. The slide E is provided at its upper end and outer side with two laterally and outwardly projecting horizontally spaced parallel arms e, and a pivotal rod G is arranged horizontally between and extends through and beyond the outer sides of said arms, and a metal frame H has arms h rotatably mounted on said pivotal rod at the outer 15 sides of the slide-arms e. The frame H is parallel with the slide E in the lower position of the slide, as shown in Fig. 3, and it will be observed that in said position said frame extends vertically upwardly into 20 proximity to the forward portion 10 of the chair-arm. The frame H is provided in its outer side edges with grooves or recesses 18 extending longitudinally and from end to end of said edges, which recesses are engaged in said position of the slide by flanges 25 21 formed on the outer ends of arms 20 with which the bars d are provided a short distance below the chair-arm. That is, the outer ends of the arms 20 project into the recesses 18 when the slide is in its lower position shown in Figs. 3, 4 and 5, and thereby operate to prevent lateral displacement of the frame H, and the relative location of the parts is such that said frame is arranged wholly above the arms 20 in the upper position of the slide, as shown in Fig. 30 6, so as to permit swinging of said frame in a vertical plane over and onto the shelf-forming forward portion 10 of the chair-arm, as shown in Fig. 7. The pivoted frame H is provided at its outer side with two spaced wooden bars 22 which are parallel with the axis of the frame, and a wooden table-leaf 23 is secured to said bars in any 35 approved manner and arranged substantially vertically in the lower position of the slide E. Obviously the frame H and the connected table-leaf are in position to be swung over and onto the shelf-forming forward portion 10 of the chair-arm C upon the actuation of the slide from its lower position, shown in Fig. 3, into its upper position, shown in Fig. 6, and said table-leaf is in position ready for use when it is swung 40 over and onto said arm, as shown in Fig. 7.

The frame H is preferably provided with a V-shaped groove 24 shown formed in the lower transverse edge of said frame when said frame is in a vertical position, shown in Figs. 3 and 6, and said groove extends 70 from end to end of said edge and facilitates guiding of said frame to bring the recesses 18 of the frame into engagement with the flanges 21 of the slide-arms 20 during the lowering of said frame upon actuating said frame from the position shown in Fig. 7 into the position shown in Fig. 6. The table-leaf 23 is preferably provided with a pull or handle 25 shown in Figs. 2 and 3. I would also remark that preferably each arm 80 e of the slide has a downwardly projecting member 26 arranged below the axis of the frame H and that said frame abuts against said projecting member in the lower position of the slide, as shown in Fig. 3, and 85 during the movement of the slide, and consequently the members 26 of the slide-arms e operate to prevent outward swinging of said frame at any point during the travel of the slide. 90

What I claim is:—

1. In a chair, an arm arranged at one side and above the seat of the chair and extending forwardly beyond said seat, a standard arranged at the forward portion of said arm and provided at its outer side with two oppositely arranged upright members forming a slideway extending up and down the standard, a slide engaging said slideway, a pivotal rod arranged horizontally at the outer side of the aforesaid slideway-forming members and transversely of and borne by the slide, a frame mounted on said pivotal rod, and a table-leaf attached to said frame, said frame and the connected table-leaf being in position to be swung over the aforesaid portion of the chair-arm upon the actuation of the slide from its lower into its upper position. 105

2. In a chair, an arm arranged at one side and above the seat of the chair and extending forwardly beyond said seat, a standard instrumental in supporting the forward portion of said arm and provided at its outer side with two vertically arranged bars 110 which are spaced longitudinally of said arm and instrumental in forming a vertically arranged slideway, a slide engaging said slideway, a frame pivoted to the slide horizontally and at a right angle to the path of the slide and provided in its side edges with recesses extending longitudinally of said edges, said frame being parallel with the slide in the lower position of the slide, and a table-leaf attached to said pivoted frame, 115 said frame and the connected table-leaf being in position to be swung over the aforesaid portion of the aforesaid arm upon the actuation of the aforesaid slide from its lower into its upper position, and the afore- 120 125 130 135

said bars being provided with arms projecting into the aforesaid recesses in the lower position of the slide.

3. In a chair, an arm arranged at one side and above the seat of the chair and extending forwardly beyond said seat, a standard instrumental in supporting the forward portion of said arm and provided at its outer side with a slideway extending up and down the standard, a slide engaging said slideway and provided at its outer side with two laterally and outwardly projecting horizontally spaced arms, a pivotal rod arranged horizontally and borne by said arms of the slide, a frame having arms mounted on said pivotal rod, a table-leaf attached to said frame, said frame and the connected table-leaf being in position to be swung over the aforesaid portion of the chair-arm upon the actuation of the slide from its lower into its upper position, and means for preventing outward swinging of said frame at any point during the travel of the slide.

4. In a chair, an arm arranged at one side and above the seat of the chair and extending forwardly beyond said seat, a standard instrumental in supporting the forward portion of said arm and provided at its outer side with two upright bars which are spaced longitudinally of said arm and instrumental in forming a slideway extending up and down the standard, a slide engaging said slideway, a metal frame pivoted to the slide horizontally and transversely of the path of the slide, said frame being parallel with the slide in the lower position of the slide and provided at its outer side with spaced wooden bars, and a table-leaf secured to said bars and arranged substantially vertically in the lower position of the slide, the aforesaid frame and the connected table-leaf being in position to be swung onto the aforesaid portion of the aforesaid arm upon the actuation of said slide from its lower into its upper position.

5. In a chair, an arm arranged at one side and above the seat of the chair and extending forwardly beyond said seat, a standard instrumental in supporting the forward portion of said arm and provided at its outer side with a slideway extending up and down the standard, a slide engaging said slideway and provided at its outer side with two laterally and outwardly projecting horizontally spaced arms, a pivotal rod arranged horizontally and borne by said arms of the slide, a frame having arms mounted on said pivotal rod, and a table-leaf attached to said frame, said frame and the connected table-leaf being in position to be swung over the aforesaid portion of the chair-arm upon the actuation of the slide from its lower into its upper position, the aforesaid arms of the slide having downwardly projecting members arranged below the axis of

the aforesaid frame and in position to prevent outward swinging of said frame at any point during the travel of the slide.

6. In a chair, an arm arranged at one side and above the seat of the chair and extending forwardly beyond said seat, a standard arranged at the forward portion of said arm and provided at its outer side with two upright bars which are spaced longitudinally of said arm and instrumental in forming a slideway extending up and down the standard, a slide engaging said slideway, a frame pivoted to the slide horizontally and transversely of the path of the slide, and a table-leaf connected to said frame, said frame and the connected table-leaf being arranged to be swung onto the aforesaid portion of the chair-arm upon the actuation of the slide from its lower into its upper position, and the aforesaid bars being provided with flanges which extend longitudinally of the bars and overlap the outer side of the slide and are long enough to prevent displacement of the slide laterally outwardly in any position of the slide.

7. In a chair, an arm arranged at one side and above the seat of the chair and extending forwardly beyond said seat, a standard arranged at the forward portion of said arm and provided at its outer side with two upright bars which are spaced longitudinally of said arm and instrumental in forming a slideway extending up and down the standard, a slide engaging said slideway, a frame pivoted to the slide horizontally and transversely of the path of the slide, and a table-leaf connected to said frame, said frame and the connected table-leaf being arranged to be swung onto the aforesaid portion of the chair-arm upon the actuation of the slide from its lower into its upper position, the aforesaid bars having arms instrumental in preventing lateral movement of the aforesaid frame in the lower position of the slide, and the relative arrangement of the parts being such that said frame is arranged wholly above said arms in the upper position of the slide.

8. In a chair, an arm arranged at one side and above the seat of the chair and extending forwardly beyond said seat, a standard instrumental in supporting the forward portion of said arm and provided at its outer side with two upright bars which are spaced longitudinally of said arm and instrumental in forming a slideway extending up and down the standard, a slide engaging said slideway, a frame pivoted to the slide horizontally and transversely of the path of the slide, and a table-leaf connected to said frame, said frame and the connected table-leaf being arranged to be swung onto the aforesaid portion of the chair-arm upon the actuation of the slide from its lower into its upper position, the aforesaid bars being pro-

vided with flanges which extend longitudinally of the bars and overlap the outer side of the slide and are long enough to prevent displacement of the slide laterally outwardly in any position of the slide, said bars also having arms instrumental in preventing lateral movement of the aforesaid frame in the lower position of the slide, and the relative arrangement of the parts being 10 such that said frame is arranged wholly

above said arms in the upper position of the slide.

In testimony whereof, I sign the foregoing specification, in the presence of two witnesses.

BELA KORMENDY.
